(57) **CLAIM**

The ornamental design for an adapter with closing device for a pressurized dispensing container, as shown and described.

DESCRIPTION

FIG. 1 is a top-front perspective view of an adapter with closing device for a pressurized dispensing container showing the design.

FIG. 2 is a bottom-back perspective view of the adapter with closing device for a pressurized dispensing container of FIG. 1.

FIG. 3 is an enlarged top-front perspective view of the adapter with closing device for a pressurized dispensing container of FIG. 1.

FIG. 4 is a first side elevation view of the adapter with closing device for a pressurized dispensing container of FIG. 1.

FIG. 5 is a second side elevation view of the adapter with closing device for a pressurized dispensing container of FIG. 1.

FIG. 6 is a top view of the adapter with closing device for a pressurized dispensing container of FIG. 1.

FIG. 7 is a bottom view of the adapter with closing device for a pressurized dispensing container of FIG. 1.

FIG. 8 is a front elevation view of the adapter with closing device for a pressurized dispensing container of FIG. 1.

FIG. 9 is a back elevation view of the adapter with closing device for a pressurized dispensing container of FIG. 1.

FIG. 10 is a front elevation view of the adapter with closing device for a pressurized dispensing container of FIG. 1, shown in an alternate environment of use; and,

FIG. 11 is a front elevation view of the adapter with closing device for a pressurized dispensing container of FIG. 1, shown in a second alternate environment of use.

The dot-dash broken lines define, but are not included in, the boundaries of the claimed design. The broken lines and portions within the broken lines are included for the purpose of illustrating environmental structure and form no part of the claimed design.

1 Claim, 5 Drawing Sheets
